(57) **CLAIM**

The ornamental design for a visor notepad holder, as shown and described.

DESCRIPTION

FIG. 1 is a perspective view of a visor notepad holder showing my new design;

FIG. 2 is a front elevational view thereof;

FIG. 3 is a rear elevational view thereof;

FIG. 4 is a left side elevational view thereof, the right side being a mirror image thereof;

FIG. 5 is a bottom plan view thereof; and,

FIG. 6 is a top plan view thereof.

The right side elevational view, not shown, is a mirror image of the left side elevational view of FIG. 4.
